DESIGN FOR A SCALE

Harry Preble, Jr., New York, N. Y., assignor to
The Jacobs Bros. Co. Inc., Brooklyn, N. Y., a
corporation of New York

Application September 12, 1942, Serial No. 108,196

Term of patent 7 years

To all whom it may concern:

Be it known that I, Harry Preble, Jr., a citizen of the United States, residing at New York, county of New York, and State of New York, have invented a new, original, and ornamental Design for a Scale, of which the following is a specification, reference being had to the accompanying drawing, forming a part thereof, wherein:

Fig. 1 is a front elevational view of a scale showing my new design; and

Fig. 2 is an end elevational view thereof.
The essential and characterizing features of my design are shown in full lines in the drawing.

I claim:

The ornamental design for a scale, as shown and described.

HARRY PREBLE, JR.
